UNITED STATES PATENT OFFICE.

PAUL STRANGE, OF NEENAH, WISCONSIN, ASSIGNOR TO JOHN STRANGE PAUL COMPANY, OF MENASHA, WISCONSIN, A CORPORATION OF WISCONSIN.

PAIL.

Application filed February 11, 1920. Serial No. 357,940.

To all whom it may concern:

Be it known that I, PAUL STRANGE, a citizen of the United States, residing at Neenah, in the county of Winnebago and State of Wisconsin, have invented certain new and useful Improvements in Pails, of which the following is a specification.

This invention relates to improvements in pails, particularly those of the type forming the subject matter of U. S. Letters Patent No. 1,118,895, the objects of the invention being to provide a container of increased strength, carrying capacity and durability, which may be more conveniently handled, both empty and filled, in packing, sealing and shipping, and which will sustain a greater weight in storage or in transit, than those of earlier design.

Other features of advantage will become apparent as the nature of the improvements is better understood from the following detailed description of a preferred embodiment of the invention which is based upon the accompanying illustrative drawings. It will be understood, however, that the drawings and description are exemplary only, and are not to be taken as suggestive of a limitation in the possibilities of application of the invention or as unnecessarily limiting the scope of the appended claims.

In the drawings—

Fig. 1 is a perspective view of a pail with the cover sealed;

Fig. 2 is an elevation showing the cover slightly raised;

Fig. 3 is a top view;

Fig. 4 is a vertical section through the pail and sealed cover;

Fig. 5 is a detailed sectional view showing the construction of the cover and the manner in which it is sealed to the body of the pail;

Fig. 6 is a sectional view showing constructional features at the bottom of the pail.

Having reference to the drawings, the numeral 10 designates the body portion or downwardly converging side wall of a fibre board pail. A supporting hoop 11, a bottom 12 and a strengthening hoop 13 are introduced in that order into the top of the pail and pressed downwardly until the lower edge of hoop 11 is flush with the lower edge of the side wall 10, the inner lower portion of said side wall having been previous-

ly coated with glue or other mucilaginous substance. The members 11, 12 and 13 are so proportioned with respect to the side wall and to each other as to fit tightly together.

To protect the lower edge of the pail and to additionally support the bottom 12, a flanged metal band 14 is glued and stapled to the exterior of the side wall 10, the flange portion 15 thereof being turned inwardly and extending beneath the hoop 11, as clearly shown in Fig. 6.

A hoop 16, a wire ring 17 and another hoop 18, of such proportions as to snugly engage the upper outer portion of the side wall 10 are glued to the latter and stapled together and to the side wall. The wire ring 17 is bent to provide a plurality of ears 19, diametrically opposed in pairs to receive the bail 20 and the cover sealing wires 21.

The cover 22 is of equal diameter with the top of the pail, and is provided at its outer edge with an angular shaped protective metal band 23, the depending portion 24 of which encircles the upper end of the body portion and the lateral flange 25 of which extends over the edge of the cover. A pair of wooden cross strips 26 are fastened to the cover by staples, as indicated at 27, or by other suitable means, the ends thereof overlying the lateral flange of the band 23, thus making the cover a unitary member, which is much more easily handled in shipping, packing and sealing than was the case when the cover and band were not fastened together.

The strips 26 also form supports for the sealing wires 21, the ends of which are bent around the unoccupied ears 19. Additional advantages in providing the cross strips are that the pail is thereby made capable of sustaining a heavier superposed weight, and may not readily be lifted by the sealing wires.

I claim:

1. In a pail the combination with a body portion, of a cover, cross strips overlying the cover, and sealing wires extending along said cross strips and having their ends secured at the sides of the body portion.

2. In a pail the combination with a body portion, of a cover, a depending angular metal band seated upon the edge of the cover, cross strips overlying the cover and band, and sealing wires extending along said

cross strips and having their ends secured at the sides of the body portion.

3. In a pail the combination with a body portion, having near the upper end thereof a wire ring provided with ears, of a cover, a depending angular metal band seated upon the edge of said cover, cross strips fastened to the top of the cover and overlying said band, and sealing wires extending along said cross strips and adapted to be secured to the ears of said ring.

4. A container comprising a frusto-conical body wall, a bottom having a peripheral contact with the inner face of the body wall, a frusto-conical hoop above the bottom having peripheral face contact with the body wall and marginal contact with the bottom about its edge to retain it against upward displacement, said hoop being secured to the body wall, a second frusto-conical hoop having peripheral face contact with the body wall below the bottom and engaging the latter about its edge to hold same against downward displacement, and a rigid band constraining the body wall over the area of

contact of the bottom therewith and extending across the lower margins of the body wall and lower hoop.

5. A container comprising a body portion provided near its bottom with straight walls, a hoop secured to the lower inner end thereof, a bottom resting upon said hoop, a second hoop secured to the lower inner end of said body portion above said bottom and in contact therewith, the upper margin of said second hoop providing an abrupt circular ledge within the container near its bottom to support the bottom portion of a similar container when telescoped therein, and a flanged band constraining the body wall over the area of contact of the bottom therewith and extending inwardly under the lower edges of the same and the lower hoop.

In witness whereof, I have hereunto signed my name in the presence of two subscribing witnesses.

PAUL STRANGE.
